UNITED STATES PATENT OFFICE.

RALPH M. DYAR, OF GROSSE POINTE FARMS, MICHIGAN.

FIRE STOP.

Application filed August 30, 1921. Serial No. 496,983.

To all whom it may concern:

Be it known that I, RALPH M. DYAR, a citizen of the United States, residing at Grosse Pointe Farms, in the county of Wayne and State of Michigan, have invented a new and useful Fire Stop, of which the following is a specification.

This invention relates to fire stops used in frame building construction. In such building, passages are formed in the walls between the studding and in the floors between the floor joists. These passages are quite objectionable as they form flues along which fire may be carried. They also form passages and harborages for rats and mice and other vermin. It is common practice to stop off these passages by fire stops, that is by fastening a board between the studding of the joists in such a manner that the passage is entirely closed. These wooden fire stops are expensive to install and only partially effective as they may be destroyed by fire and they may also be easily gnawed through by rodents.

It is an object of this invention to provide a fire stop which may be secured in place by a few blows of a hammer and which will be so constructed that accurate spacing of the studding and joists is not absolutely necessary to its use.

A further object of this invention is to provide a stop which is fire and vermin proof, sheet iron being a convenient material having these characteristics.

A still further object of this invention is to provide a fire stop which can be cheaply formed from light and inexpensive material and which, when completed, will have considerable mechanical strength.

Further objects and advantages will become evident hereinafter.

Referring to the drawing which is for illustrative purposes only:

Fig. 1 is a perspective view showing a portion of a building with fire stops of my invention installed therein.

Fig. 2 is a plan view of the fire stop illustrated in Fig. 1.

Fig. 3 is an elevational detail showing the manner in which the fire stop illustrated in Fig. 1 is installed.

Fig. 4 is a plan view of another form of my invention.

Fig. 5 is an elevational detail showing the manner in which the fire stop illustrated in Fig. 4 is installed.

Fig. 6 is a plan view of still another form of my invention.

Fig. 7 is an elevational detail showing the manner of installing the fire stop illustrated in Fig. 6.

As shown in Fig. 1 of the drawing, the customary construction of wood frame buildings includes wall studs 11 upon which are mounted a lath and plaster or other suitable finish 12, and floor joists 13 supporting flooring 14. Between the wall studs 11 and the floor joists 13 fire stops 20 are installed for the purpose of obstructing the passages formed therebetween and thus preventing fire started in one portion of the structure from being transferred to another portion thereof by drafts through said passages, and to prevent rodents from using these passages, as hereinbefore described.

The fire stop 20 consists of a sheet metal plate 21 provided with stiffening corrugations 22, and having diagonally directed end portions 23 upon which are formed prongs

24 for engagement with the building members 11. The over all length of the fire stop is slightly greater than the distance between the building members by which same is supported, and to install the fire stop it is only necessary to force it in between the building members 11 as illustrated in Fig. 3

by the dotted lines 25, the diagonal ends 23 being bent inwardly to a slightly more acute angle. A block is placed upon the fire stop and several driving blows struck at the ends as illustrated by the arrows 26. The downward force thereby exerted is transferred through the diagonal ends 23 and is resolved into laterally exerted force to accomplish the imbedding of the serrations 24

firmly in the surface of the members 11, as illustrated in full lines 27 in the figures. By changing the angle at which the ends 23 are bent, it is possible to use this fire stop between members variably spaced within cer-

tain limits.

Another embodiment of my invention, Figs. 4 and 5, consists of a plate 30 provided with serrations 31 upon each end thereof and stiffening corrugations 32 extending from points near the center of the sheet so that a flexible web portion 32 is left at the center of the sheet. The two stiffened portions 34 then act as separate rigid members having a bendable connecting web. By changing the angular relationship between the portions 34, by bending the structure at

the web 33 as illustrated in Fig. 5, the distance between the serrated ends is varied to suit the spacing of the building members. It will be seen that this type of construction allows considerable latitude in the spacing of the building members.

The installation of this type of fire stop is accomplished in a manner similar to that shown in Fig. 3. The fire stop 30 is placed 10 between the members 11, as illustrated by the dotted lines in Fig. 5, and several downward blows are struck as indicated by the arrow 35 which forces downward into the position indicated in full lines and the serrations are imbedded in the surfaces of the members 11.

The form of my invention shown in Figs. 6 and 7 consists of a metal plate 40 provided with edge serrations 41 and a stamped semi-circular bead 42 which divides the fire stop into two portions 43 provided with stiffening corrugations 44. The stop 40 is placed 20 between the building members 11 as indicated by the full lines in Fig. 7. A block 25 46 is then placed under the bead 42 and the bead is flattened with a hammer causing the portions 43 to be forced apart and the serrations projected into the surfaces of the building members 11.

30 The serrations which I use upon the ends of these fire stops provide expedient means of engaging the surfaces of the building members.

It will be perceived that the principal 35 feature of my invention resides in so forming a sheet of material that bent portions will be provided to furnish an expanding means for the fire stop, in the flattening of these bent portions by driving with a suitable instrument. The cheap cost of manufacture of my invention and the facility with which it may be installed makes it a 40 valuable adjunct in the building industries.

I claim as my invention:

45 1. In a fire stop for obstructing wall and floor passages in a frame building, a plate of greater length than the space which it is to occupy, having bent portions so formed within the edges of said plate that the effective length thereof will be reduced sufficiently to allow it to be placed between the building members enclosing the passage to be obstructed, and that said plate may be expanded to be secured in position by the straightening of said bent portions.

50 2. In a fire stop for obstructing wall and floor passages in a frame building, the combination of: a plate of greater length than the space which it is to occupy, certain of the edges of said plate being prepared to provide engagement with certain of the walls of a passage; and bent portions so formed within the edges of said plate that the effective length thereof will be reduced 55 sufficiently to allow it to be placed between

the building members enclosing the passage to be obstructed, and that said plate may be expanded to be secured in position by the straightening of said bent portion.

3. In a fire stop for obstructing wall and 70 floor passages in a frame building, the combination of: a plate of greater length than the space which it is to occupy, certain of the edges of said plate being prepared to provide engagement with certain of the 75 walls of a passage; and bent portions so formed within the edges of said plate, parallel with said engagement edges, that the effective length thereof will be reduced sufficiently to allow it to be placed between the 80 building members enclosing the passage to be obstructed, and that said plate may be expanded to be secured in position by the straightening of said bent portions.

4. In a fire stop for obstructing wall and 85 floor passages in a frame building, the combination of: a plate of greater length than the space it is to occupy; prongs formed upon the ends of said plate to provide engagement with certain of the walls of a passage; and portions diagonally bent upon the 90 ends of said plate so that the effective length thereof will be reduced sufficiently to allow placement between the building members enclosing the passage to be obstructed and 95 so that said plate may be expanded to be secured in position by relatively straightening said bent portions.

5. In a fire stop for obstructing wall and 100 floor passages in a frame building, the combination of: a plate of greater length than the space which it is to occupy, certain of the edges of said plate being prepared to provide engagement with certain of the 105 walls of a passage; corrugations formed in said plate to stiffen same; and bent portions so formed in said plate that the effective length thereof will be reduced sufficiently to allow it to be placed between the building members enclosing the passage to be obstructed, and that said plate may be expanded to be secured in position by the straightening of 110 said bent portions.

6. In a fire stop for obstructing wall and 115 floor passages in a frame building, the combination of: a plate of greater length than the space which it is to occupy, certain of the edges of said plate being prepared to provide engagement with certain of the walls of a passage; corrugations formed in 120 said plate to stiffen same; and bent portions so formed in said plate, parallel with said engagement edges, that the effective length thereof will be reduced sufficiently to allow it to be placed between the building members enclosing the passage to be obstructed, and that said plate may be expanded to be secured in position by the straightening of 125 said bent portions.

7. In a fire stop for obstructing wall and 130

floor passages in a frame building, the combination of: a plate of greater length than the space it is to occupy; corrugations formed in said plate to stiffen same; prongs formed upon the ends of said plate to provide engagement with certain of the walls of a passage; and portions diagonally bent upon the ends of said plate so that the effective length thereof will be reduced sufficient-

ly to allow placement between the building members enclosing the passage to be obstructed and so that said plate may be expanded to be secured in position by relatively straightening said bent portions.

In testimony whereof, I have hereunto set my hand at Los Angeles, California, this 15th day of August 1921.

RALPH M. DYAR.
